CLAIM

The ornamental design for a telephone, as shown and described.

DESCRIPTION

FIG. 1 is a front, right side, bottom perspective view of a telephone;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a front elevational view thereof showing a state in which the handset is removed from the base of the telephone; and,

FIG. 9 is a right side view thereof in which a leg and display unit are each shown in an alternate position.
